Patented Sept. 24, 1918.

Inventor:

Lewis Edward Johnston

UNITED STATES PATENT OFFICE.

LEWIS EDWARD JOHNSTON, OF SULLIVAN, MISSOURI.

AUTOMOBILE SPARK-PLUG.

1,280,113.

Specification of Letters Patent. Patented Sept. 24, 1918.

Application filed May 1, 1917. Serial No. 165,802.

To all whom it may concern:

Be it known that I, LEWIS EDWARD JOHNSTON, a citizen of the United States, and a resident of the city of Sullivan, county of 5 Franklin, and State of Missouri, have invented new and useful Improvements in Automobile Spark-Plugs, of which the following is a specification.

My invention relates to improvements in 10 spark plugs of the type usually employed in connection with internal combustion engines, the principal object of my invention being to provide a spark plug having a novel construction of certain features and details 15 wherein the efficiency and reliability of operation of the device shall be materially increased.

One of the great difficulties encounter in 20 the use of spark plugs on internal combustion engines is the short-circuiting of the current passing through the plug, this action being due to the fact that the electrodes become coated with a deposit of carbon, soot, oil or other short-circuiting material 25 and in time, this accumulation is effective in preventing the spark plug from performing its intended functions.

I propose to overcome the objection just noted by locating on the central electrode of 30 the plug, a disk, the edge or periphery of which lies immediately adjacent to the inner annular end of the spark plug body or shell, the same serving as the outer electrode, such construction providing a pair of annular 35 edges between which the current may pass at any point to produce a spark. In other words, my improved construction provides for an annular spark gap of considerable circumference, and if the greater portions 40 of the two edges of the electrodes are coated with carbon or the like, there will still be sufficient space on the edges for the production of the spark, thus enabling the plug to perform its normal functions.

One of the objects of my invention is to 45 adjustably mount the disk upon the central electrode, thereby permitting the spark gap or space between the electrodes to be regulated according to the requirements of the 50 particular coil with which the spark plug is employed.

A further object of my invention is to 55 construct the inner end of the spark plug so as to prevent the accumulation of short-cir- cuiting material on the spark points or

edges, thereby tending to maintain the same in a clean and serviceable condition.

With the foregoing and other objects in view, my invention consists in certain novel features of construction and arrangement of 60 parts, hereinafter more fully described and claimed, and illustrated in the accompanying drawings, in which—

Figure 1 is a side elevational view of a 65 spark plug constructed in accordance with my invention;

Fig. 2 is a vertical section taken lengthwise through the center of the spark plug with a portion of the insulated core thereof in elevation.

Referring by numerals to the accompanying drawings, which illustrate a practical embodiment of my invention, 10 designates the outer shell or body of the plug, the same being formed of metal and provided intermediate its ends with an internally arranged shoulder 11. The upper end of this shell or body is internally threaded as designated by 12, and the lower end is externally threaded as designated by 13 in order that 70 said body may be screw-seated in the wall of an internal combustion engine.

A core 14 of insulation, preferably porcelain is provided intermediate its ends with an annular rib 15 and when this core is 75 properly positioned in the shell or body 10, the shoulder on the underside of said rib bears directly upon a gasket or packing ring 16, which latter rests directly upon the shoulder 11.

A gland or packing ring 17 is screwed into 80 the threaded upper end of the body 10, the lower end of said gland or ring bearing directly upon the shoulder above the rib 15.

Extending axially through the core 14 is 85 the central electrode 18, the same being in the form of a metal rod, both ends of which are threaded and formed on or fixed to the lower portion of said rod and immediately above the threaded lower end thereof is a 90 disk 19 which fits snugly within a recess 20 formed in the lower end of core 14.

A portion of the threaded lower end of 95 this electrode extends below the lower end of the shell or body 10 and screw-seated upon said lower portion is a disk 21, the top 100 surface of which is preferably flat and the undersurface being convex. Formed through this disk is an aperture 22 which is adapted to receive a suitable tool whereby the disk 110

may be screwed up or down upon the central electrode to regulate the distance between the edge of said disk and the annular lower edge of body 10. The extreme lower 5 end of electrode 18 is pointed as designated by 23. The threaded upper portion of electrode 18 is provided with nuts 24 and 25 between which the terminal of a conductor may be clamped and interposed between the 10 nut 24 and the top of core 14 is a packing disk 26.

It will be understood that the electric current delivered to the spark plug by a line connection clamped between the nuts 24 and 15 25 passes downward through electrode 18, from thence through disk 21 and in jumping to the lower edge of the cylindrical body 10, produces a spark, thereby igniting the compressed charge within the engine cylinder. 20 The width of the spark gap can readily be regulated by adjusting the position of disk 21 on the threaded lower portion of electrode 18, this operation being accomplished by means of a suitable tool inserted in the 25 aperture 22 and rotating said disk 21.

It will be noted that the disk 21 forming the central electrode has a diameter that is equal to or slightly larger than the internal diameter of the lower portion of shell 10 30 and for this reason any carbon or oil which may be thrown onto the convex undersurface of said disk 21 will be directed outwardly and upwardly and thus be prevented from entering and accumulating within the 35 chamber between said disk 21 and the lower end of the porcelain body 14.

It has been demonstrated in practice that there is no tendency of carbon or the like to accumulate on the convex underside of disk 40 21 and the pointed end 23 of electrode 18, and it is believed that this self-cleaning action is due to the sweeping or wiping action of the compressed gases during the firing action or while under combustion. Further, 45 it has been noted that the spark produced by my improved plug will travel from one point to another around the annular spark gap, and by virtue of the fact that said spark gap is continuous or in the form of a circle 50 the plug will continue to perform its functions even though considerable portions of the edge of disk 21 and the lower edge of shell 10 be covered with a coating or deposit of carbon or the like.

55 For this reason my improved spark plug can be used continuously for a much greater period of time than a spark plug having a spark gap formed between the attenuated ends of a pair of electrodes.

60 It will be readily understood that minor changes in the size, form and construction of the various parts of my improved spark

plug can be made and substituted for those herein shown and described, without departing from the spirit of my invention, the 65 scope of which is set forth in the appended claims.

I claim:

1. The herein described spark plug comprising a substantially tubular body, a core 70 of insulation within said body, the lower end of which core terminates a short distance above the lower end of the tubular body, a rod passing through the core, the lower portion of which rod is threaded and projects 75 below the lower end of the tubular body, a nut mounted on the threaded lower end of the rod and occupying the recess formed in the lower end of the core, and an electrode in the form of a disk positioned on the 80 threaded lower end of the rod below the cylindrical body, said disk having a diameter slightly greater than the internal diameter of the tubular body, and provided with a flat top surface and a smooth convex lower 85 face, and the end of the rod which projects below said disk being pointed.

2. The herein described spark plug comprising a substantially tubular body, a core 90 of insulation within said body, the lower end of which core terminates a short distance above the lower end of the tubular body, a rod passing through the core, the lower portion of which rod is threaded and projects 95 below the lower end of the tubular body, a nut mounted on the threaded lower end of the rod and occupying the recess formed in the lower end of the core, and an electrode in the form of a disk positioned on the threaded lower end of the rod below 100 the cylindrical body, said disk having a diameter slightly greater than the internal diameter of the tubular body, and said disk having a flat top surface and a smooth convex lower face and provided with an eccentrically arranged aperture adapted to receive 105 a tool whereby said disk can be screwed on to or from the threaded lower end of said rod.

3. A spark plug having a substantially 110 tubular body, a core of insulation within said tubular body, a rod passing through said core, the lower portion of said rod being threaded and projecting a substantial distance below the lower end of the tubular 115 body, the extreme lower end of said rod being pointed, and an electrode of disk form screw-seated on the threaded lower portion of the rod, the edge of which disk is disposed adjacent to the lower end of the tubular body, and said disk having a smooth convex lower face.

LEWIS EDWARD JOHNSTON.
